M. R. GOWING

SELECTIVE SIGNALING CIRCUITS

Filed July 9, 1921

Inventor:
Maurice R. Gowing
by C. C. Sprague, Att'y.

UNITED STATES PATENT OFFICE.

MAURICE R. GOWING, OF MOUNTAIN LAKES, NEW JERSEY, ASSIGNOR TO WESTERN ELECTRIC COMPANY, INCORPORATED, OF NEW YORK, N. Y., A CORPORATION OF NEW YORK.

SELECTIVE SIGNALING CIRCUITS.

Application filed July 9, 1921. Serial No. 483,432.

To all whom it may concern:

Be it known that I, MAURICE R. GOWING, a citizen of the United States, residing at Mountain Lakes, in the county of Morris, 5 State of New Jersey, have invented certain new and useful Improvements in Selective Signaling Circuits, of which the following is a full, clear, concise, and exact description.

10 This invention relates to selective signaling circuits and more particularly to selective circuits for associating the sending and receiving branches of a two-way alternating current signaling system with a common 15 transmission medium or line. The object of the invention is to provide a simple and effective arrangement of selective circuits for such a system.

In its preferred form, the invention is 20 embodied in a carrier wave telephone system in which a plurality of two-way conversations may be carried on over a common transmission line. Distinctive frequencies are used for transmissions in opposite directions and also for different transmissions in the same direction. Band-pass filters having series and shunt impedance elements are used in the sending and receiving circuits to allow the passage of current of desired frequencies to the respective circuits. The shunt sections of all of the filters, both sending and receiving, are connected in series with each other and with the common transmission line.

35 This embodiment of the invention is shown in the drawing in which Fig. 1 is a multiplex terminal of a carrier wave telephone system and Fig. 2 a modification thereof.

40 Referring now to Fig. 1, multiplex carrier terminal station C and an ordinary telephone line L are connected to a common transmission line ML by means of a "carrier composite set" comprising a high-pass filter HPF and a low-pass filter LPF. The carrier terminal as shown comprises two two-way channels I and II. These channels have transmitting branches TB¹ and TB², respectively, and receiving branches RB¹ 45 and RB², respectively.

An ordinary telephone line L¹ connects an ordinary subscriber's telephone station or a telephone exchange A to channel I. The line L¹ is conjugately connected to the transmitting branch TB¹ and the receiving branch RB¹ by means of the conjugate transformer or hybrid coil 5. The balancing network N¹ connected to coil 5, balances the line L¹. In the transmitting branch TB¹ is an oscillation generator O¹, a modulator M¹ 55 and a modulator band filter MBF¹. The receiving branch RB¹ comprises a detector band filter DBF¹, a demodulator D¹, a demodulator amplifier DA¹ and a low pass filter LPF¹.

The oscillator O¹, modulator M¹, demodulator D¹ and demodulator amplifier DA¹ may be of any suitable design, but are preferably of the vacuum tube type. Devices suitable for this purpose are described by 70 E. H. Colpitts and O. B. Blackwell, in a paper entitled "Carrier current telephony and telegraphy" published in the Journal of the American Institute of Electrical Engineers for April, May and June, 1921. The 75 modulator band filter MBF¹ and demodulator band filter DBF¹ comprise series and shunt impedance elements and are preferably of the general type disclosed in Campbell Patent No. 1,227,113 of May 22, 1917. 80

A subscriber's station or ordinary telephone exchange B is connected to channel II by means of an ordinary telephone line L². Channel II is similar to channel I except that the constants of the filters used 85 therein are such as to take care of the frequencies individual thereto.

The shunt impedance elements 6, 7, 8 and 9 of the several band filters are all connected in series with each other and with the primary of transformer 10 to make up a common terminal circuit. By means of transformer 10, this common terminal circuit is inductively connected through the high-pass filter HPF to the common line ML. 95

At the distant end of the common line ML is located another carrier terminal station adapted to cooperate with the terminal station shown. For each transmitting branch of the station shown, there is a co- 100

operating receiving branch at the distant station and for each receiving branch of the station shown, there is a cooperating transmitting branch at the distant station.

5 Distinctive frequencies are used for transmissions in opposite directions and for different transmissions in the same direction. Thus, each of the band filters MBF¹, DBF¹, MBF² and DBF² are adapted to pass a distinctive band of frequencies, which frequencies are used for the transmission, characteristic of that branch.

10 In Fig. 1, two channels only of a multiplex system are shown, but it is to be understood that a greater or less number may be used. Regardless of the number of channels in the system, the end sections of all the band filters would be connected in series with each other and with the common line 15 through a transformer such as transformer 10.

15 In an actual system which has been manufactured, carrier frequencies of 6, 9 and 12 kilocycles are used for transmission in one 20 direction and frequencies of 15, 18 and 21 kilocycles for transmission in the opposite direction. In this system, the lower side bands of frequencies are used with the lower 25 carrier frequencies and the upper side bands, with the higher frequencies. Also in this 30 system, both the carrier frequency itself and the side band corresponding to the telephone message are transmitted from the sending station to the receiving station over the common 35 line.

40 In the modification of Fig. 2, the common terminal circuit, comprising the shunt impedance elements 6, 7, 8 and 9 connected in series with each other, is conductively connected to the common line ML. In other words, the transformer 10 has been omitted. In this modification, it is to be noted, the 45 band filters in the transmitting branches are directly connected together and likewise those in the receiving branches, as distinguished from the staggered arrangement of Fig. 1. Whether or not it is desirable to use either or both of the modifications of Fig. 2 will depend upon the physical, electrical and 50 economical conditions of each installation.

55 While the invention has been described in its embodiment in a carrier wave telephone system, it may well be embodied in other systems where selective circuits are required. The scope of the invention is defined by the accompanying claims.

What is claimed is:

60 1. In a carrier signaling system, a terminal station, a transmitting branch at said station, a receiving branch also at said station, a band filter in each of said branches, each of said filters having a shunt impedance element, a common transmission medium, and means to connect a shunt impedance

65 element of a filter in said transmitting branch and a shunt impedance element of a filter in said receiving branch in series with each other and with the common transmission medium.

70 2. In a carrier wave signaling system, a common transmission line, a carrier terminal station, a transmitting branch and a receiving branch at said station, a source of speech modulated carrier waves a band filter having shunt impedance elements for 75 said transmitting branch, a demodulator for speech modulated carrier waves, another band filter having shunt impedance elements for the receiving branch, means to connect a shunt element of a transmitting band filter and a shunt element of a receiving band filter in series with each other, and means to associate the carrier terminal with the common line.

80 3. In a multiplex signaling system, a terminal station, a transmission line, a plurality of transmitting branches at said terminal station, a plurality of receiving branches also at said terminal station, a band filter in each of said branches, each of said filters 90 having a shunt impedance element at one end thereof, means to connect all said end shunt impedance elements in series with each other, and means to associate said terminal station with said line.

95 4. In a multiplex signaling system, a terminal station, a transmission line, a collecting circuit coupled to said transmission line at said terminal station, a plurality of transmitting branches and a plurality of receiving branches at said terminal station, and a band filter in each of said transmitting and receiving branches having a shunt impedance element connected to said collecting circuit.

100 5. In a multiplex signaling system, a terminal station, a transmission line, a collecting circuit at said terminal station, a transformer having its primary winding connected to said collecting circuit and its secondary winding connected to said transmission line to enable two-way transmission between said circuit and said line, a plurality of transmitting branches and a plurality of receiving branches at said terminal station, and a band filter in each of said branches having a shunt impedance element connected to said collecting circuit.

110 6. In a multiplex signaling system, a terminal station, a transmission line, a plurality of transmitting branches and a plurality of receiving branches at said station, a source of speech modulated carrier waves associated with each of said transmitting branches, a demodulator for speech modulated waves associated with each of said receiving branches, a band filter having series and shunt impedance elements in each of

said transmitting and receiving branches to separate the respective bands of frequencies allotted thereto, there being a greater frequency separation between oppositely directed frequencies than between the frequencies transmitted in the same direction, and means to connect a shunt impedance element of each of the band filters in both said transmitting and receiving branches in series with each other and with said transmission line.

In witness whereof, I hereunto subscribe my name this 5th day of July, A. D. 1921.

MAURICE R. GOWING.
